UNITED STATES PATENT OFFICE.

JOHN B. NEIL, OF NEW YORK, N. Y., ASSIGNOR TO MATTHEW J. WHITTALL,
OF WORCESTER, MASSACHUSETTS.

DESIGN FOR CARPET.

SPECIFICATION forming part of Design No. 25,373, dated April 7, 1896.

Application filed March 6, 1896. Serial No. 582,142. Term of patent 34 years.

To all whom it may concern:

Be it known that I, JOHN B. NEIL, a citizen of the United States, residing at New York, in the county of New York and State of New York, have invented and produced a new and original Design to be Wrought into Wilton and other Carpeting in such Coloring as may be Designed, of which the following is a specification.

10 This invention comprises two parts—namely, the design A for a carpet-body and the design B for a border; and I do hereby declare that the drawing accompanying this specification gives and conveys to any one skilled in the art of carpet weaving and manufacture a clear understanding of same, and is sufficient to enable such person to use my invention.

15 The body A is decorated with groups of three 20 leaf-shaped figures surrounded by mosswork.

The border B shows the same figure groups in enlarged form with mosswork and smaller ornaments.

What I claim as my invention, and desire to secure by Letters Patent, is—

- 25 1. In a design for a carpet, the body A, substantially as shown.
2. In a design for a carpet, the border B, substantially as shown.

3. The design for carpets, consisting of the 30 body A and the border B, substantially as shown.

In testimony whereof I have hereunto set my hand in the presence of two subscribing witnesses.

JOHN B. NEIL.
